VALVED HEAD CONSTRUCTION FOR SPARKLET SYPHON

William B. Kochner, St. Louis, Mo., assignor to Knapp-Monarch Company, St. Louis, Mo., a corporation of Delaware

Application January 3, 1956, Serial No. 556,873

2 Claims. (Cl. 222—394)

This invention relates generally to a valved head construction, and more particularly to an improved valved head of the type including gas-charging valve means and dispensing control valve means for use with a sparklet syphon device.

It is a primary object of this invention to provide a unitary valved head construction for a sparklet-type syphon device having an improved charging valve which is readily replaceable while maintaining effective liquid- and gas-tight sealing closure.

It is another object to provide a valved head construction of this type, wherein a dispensing control valve and cooperating actuating means of simple, compact, low-cost, reliable, and readily serviced construction are provided, while maintaining effective liquid- and gas-tight sealing closure.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which:

Figure 1 is a side elevational view of a sparklet-type syphon device embodying the features of the present invention;

Figure 2 is a fragmentary vertical cross-sectional view, on an enlarged scale, showing details of construction of the valved head embodied in the syphon device of Figure 1;

Figure 3 is a fragmentary view similar to Figure 2 showing the dispensing flow control valve in an open-flow position;

Figure 4 is a vertical cross-sectional view taken substantially as indicated along the line 4—4 of Figure 2; and

Figure 5 is a perspective view of the dispensing control valve actuating handle.

Referring now more particularly to the drawing, I have indicated generally at 10 a syphon bottle of the type commonly designated as a "sparklet" syphon device. The syphon bottle includes a hollow vase 12 having a closed bottom supported upon a base 14 and being upwardly open for cooperation with a valve head assembly 16. The assembly 16 serves to sealingly close the vase 12, to provide valve means for introducing a pressurizing gas into the vase 12, and to control dispensing flow outwardly therethrough.

The assembly 16 includes a unitary molded body 18, of plastic or like material. The body 18 is adapted at its lower end to effect a gas- and liquid-tight connection to the upper end of the vase 12. Reference may be had to my co-pending application, Serial No. 524,091, filed July 25, 1955 for a detailed description of a suitable sealing connection. A discharge passageway 20 terminates in a nozzle 22 for discharge flow of liquid contents from within the vase 12. An internal boss 24 provides a tapped hole 26 in flow communication with the interior

2

of the vase 12. A threaded syphon tube 28 is received within the hole 26 and terminates downwardly at a point closely adjacent with the bottom of the vase 12. A bore 30 inwardly communicates the hole 26 with the passageway 20.

A discharge valve for controlling dispensing flow from the syphon bottle is provided in generally horizontal orientation within the body 18, thereby avoiding the necessity for a valve-receiving pocket within the head of substantial vertical depth, and achieving a head of compact form and size. The valve 32 is of the needle type, and cooperates with a valve seat 34 integrally formed within the body 18 intermediate the passages 30 and 20. A sealing bore 36 receives the seating or control end of the valve 32 for axially sliding movement therein. A piston portion 38 effects sliding engagement with the walls of the sealing bore 36. An annular groove 40 is formed intermediate the piston 38 and the seating end of the valve 32, and receives an O-ring 42 therein for slidably sealing engagement with the walls of the sealing bore 36 forwardly of the piston 38. In this way, the discharge valve 32 may be reciprocated for effecting control regulating of discharge flow, while at the same time providing an effective liquid- and gas-tight seal.

A valve stem portion 44 extends through an enlarged bore portion 46 within the body 18. A spring 48 within the bore 46 is biased in compression, and serves to normally urge the valve 32 into sealing engagement with the seat 34. The bore 46 terminates in an outwardly open recess which is internally threaded to receive a threaded retaining plug 50. The outer end of the valve stem 44 slidably extends through the retaining plug 50.

The outer end of the valve stem 44 carries a bearing washer 52 held in position thereon by means of a retaining washer 54. An actuating lever 56 is cooperatively secured to the stem 44 in removable manner. The lever 56 is preferably of unitary molded form, such as plastic or like material, and is internally hollow at its upper end. As best seen in Figure 5 of the drawing, the lever 56 provides at its upper end a pair of parallel spaced bearing flanges 57 and 58. The bearing flanges are contiguous with a pair of inwardly arcuate surfaces 59 and 60, which are in turn contiguous with a transverse lock flange 62. In this way, a downwardly open slot is formed by the lever end.

Below the bearing flanges 57 and 58, the lever 56 is undercut at 64. The body 18 provides a stepped portion forming a fulcrum shoulder 66 (see Figures 2 and 3) upon which the undercut 64 of the lever is adapted to seat. The body 18 provides a recessed portion 68 of sufficiently enlarged form to permit the lever end to be slipped over the bearing washer 52 and received within the body 18. The force of the spring 48 provides tight engaging contact between the bearing washer 52 and the internal surfaces provided by the arcuate portions 59 and 60.

When a manual force is exerted against the lower end of the lever 56 in a direction toward the head body 18, the upper end of the lever at the undercut 64 will pivot upon the shoulder 66, thereby effecting a withdrawal of the valve stem 44 and a consequent movement of the needle valve 32 away from its seat 34. As seen in Figure 3, a flow passage will be completed from the bore 30 to the discharge passageway 20. Upon manual release of the lever 56, the spring 48 will serve to return the valve 32 to a closed-flow position of seating engagement against the valve seat 34. Simple and effective valve actuation is obtained by this construction, while at the same time maintaining an effective liquid- and gas-tight sealing closure.

The mechanical cooperation between the lever 56 and the valve stem 44 permits a substantially horizontal ori-

tation of the elongated valve within the body 18. The valve communicates with the inner surface of the body 18 and the interior of the vase 12 therebelow only through the bore 30 and the siphon tube 28. Horizontal positioning of the valve in this way at a location substantially high within the head assembly 16 results in a smoothly continuous and unobstructed internal body surface, except for the single small tapped hole 26. Such an arrangement permits simple and thorough cleaning of all surfaces of the body 18 which are directly exposed to the fluid within the vase 12. The use of a unitary needle-type valve, an integrally formed valve seat, and the elimination of multiple-piece assemblies, achieves a construction which is sanitary and readily adapted for replacement and cleaning of parts.

As best seen in Figure 4 of the drawing, the body 18 is formed with a bore 70 which communicates inwardly with the interior of the vase 12, and which terminates outwardly in an enlarged and outwardly open recess 70'. A hollow plug member 72 of generally cylindrical form is received within the bore 70 in axially slidable manner. The plug 72 is formed with an internal bore 74 adapted to receive a flanged member 76 in axially slidable manner. The member 76 provides a piercing pin 78 at its outer end, which is of the well-known type commonly used to effect a puncture of a bulb of compressed gas.

The inner end of the plug 72 is formed with a peripheral groove 80, which receives an O-ring 82 therein for sealing contact against the bore 70. A shoulder 84 is formed forwardly of the groove 80, and receives a retaining washer 86 thereagainst. The washer 86, when snapped into position upon the shoulder 84, serves to prevent withdrawal of the plug 72 from the bore 70.

The outer end of the plug 72 is formed with an internal annular groove 88 which receives an O-ring 90 therein. The groove 88 is located outwardly of the pointed end of the piercing pin 78, and the adjacent inner wall portions of the plug 72 serve to define a bulb receiving chamber 92. In this way entry of the sealed outlet end of a conventional sparklet bulb into the plug 72, serves to effect initial sealing engagement with the O-ring 90 prior to puncture by the piercing pin 78.

The outer end of the plug 72 is slightly enlarged and externally screw-threaded at 93. The axially inward end of the portion 93 abuts the adjacent body portion which defines the outward end of the bore 70, and cooperates with the washer 86 to provide a predetermined axial positioning of the plug 72. The threaded portion 93 is spaced from the adjacent side walls of the enlarged recess 70'. In this way, a sparklet bulb may be disposed within a bulb holder of the type having an internally threaded portion, in the well-known manner, and the bulb holder may then be threaded onto the plug 72, thereby progressively feeding the bulb inwardly within the plug 72 for initial sealing contact with the O-ring 90 and subsequent piercing by the pin 78.

A check valve 94 is threaded into the inner end of the flanged member 76 for integral attachment and cooperating movement therewith. The valve 94 engages a seat 96 formed at the inner end of the plug 72. A bore 98 is formed within the valve 94 and communicates with lateral passages 100 for discharge flow. A spring 102, biased in compression, urges the flanged member 76 in an outward direction within the bore 74, thereby effecting seating engagement between the check valve 94 and the seat 96. In this way, liquid and gas flow from the interior of the vase 12 outwardly through the plug 72 is prevented.

Bores 104 and 106 provide continuous flow communication through the piercing pin 78 and the flanged member 76. The bore 98, and the passages 100 of the check valve 94 complete a flow path into the interior of the head 18 and the vase 12. It will be apparent that when a sparklet bulb engages the piercing pin 78, the flanged member 76 is slidably moved against the force of the

spring 102 to a position of limiting engagement against an internal wall portion of the plug 72. The check valve 94 is thereby moved away from the valve seat 96, so that when the piercing pin 78 punctures the bulb, direct flow communication is provided into the vase 12.

The body 18 is integrally formed with a key portion 110 which is slidably received within a cooperatively formed keyway 111 of the plug 72. In this way, rotation of the plug 72 within the bore 70 is precluded, while axial sliding movement during assembly and disassembly of parts is readily permitted.

A cover 114 is hingedly secured at 116 to the body 18. A spring latch 118 formed by a cover bracket 120 mounted within the enlarged recess 70' cooperates with the hinge 116 to retain the cover 114 in full open position. A second spring latch 122 is also provided by the cover bracket 120 for cooperation with the cover 114 to retain it in its full closed position.

It is an important aspect of the present invention that the plug member 72, which serves to support the combined bulb piercing and one-way check valve means, is removably received within the head 18. The provision of cooperating sealing means 82, retaining means 86, and key means 110, permits the achievement of a fixed positioning of the plug member 72 in liquid- and gas-tight sealing relation within the head 18, while at the same time enabling the various parts to be readily removed for cleaning or replacement. In this way, a simple and entirely mechanical assembly of parts is provided, thereby eliminating the necessity for using heat, solder, and like methods of connection which would prevent the use of plastic materials for unitary molding of the head 18. Such a construction permits convenient replacement of parts at any time without the requirement of heat or power tools.

Changes may be made in the construction and arrangement of the parts of my valved head construction for sparklet siphon without departing from the real spirit and purpose of my invention, and it is my intention to cover by the claims any modified forms of structure or use of mechanical improvements which may be reasonably included within their scope.

What I claim as new and desire to obtain by Letters Patent of the United States is:

1. A head construction for a gas-pressurized siphon device, comprising an open-ended hollow vase, a unitary body serving to sealingly close said vase and providing a downwardly directed discharge passage and an upwardly directed siphon passage forming an inward intersection therewith, said siphon and discharge passages providing means for fluid flow outwardly therethrough from the interior of said vase, said body being formed with a generally horizontally disposed bore fully enclosed within said body, said bore terminating inwardly at said passage means intersection in a valve seat integrally formed by said body and terminating outwardly in an exteriorly open recess, a unitary elongated valve member disposed in said bore and providing a head at its one end adapted when moved inwardly to sealingly engage said valve seat for closing said passage means and providing a stem at its other end extending into said recess, said valve member having an intermediate piston portion serving to slidably engage the walls of said bore, resilient sealing means carried by said valve member forwardly of said piston portion and cooperating with the walls of said bore and with said piston portion to prevent fluid flow outwardly through said bore, a retaining member removably received within said bore at its outward end, said stem extending slidably through said retaining member, spring means within said bore biased in compression between said piston portion and said retaining member to urge said valve member toward its seating position, and handle means removably secured to the outer end of said valve stem at said recess for

withdrawing said valve member against the bias of said spring toward its open position.

2. A head construction for a gas-pressurized siphon device, comprising an open-ended hollow vase, a unitary body serving to sealingly close said vase and providing a downwardly directed discharge passage and an upwardly directed siphon passage forming an inward intersection therewith, said siphon and discharge passages providing means for fluid flow outwardly therethrough from the interior of said vase, said body being formed with a generally horizontally disposed bore fully enclosed within said body, said bore terminating inwardly at said passage means intersection in a valve seat integrally formed by said body and providing an enlarged bore portion terminating outwardly in an exteriorly open recess, a unitary elongated valve member disposed in said bore, said valve member providing a head at its one end adapted when moved inwardly to sealingly engage said valve seat for closing said passage means and providing a stem at its other end extending through said enlarged bore portion into said recess, said valve member having an intermediate piston portion serving to axially slidably engage the walls of said bore, an annular groove intermediate said head and piston portion and resilient sealing means therein cooperating with the walls 25

10

of said bore and with said piston portion to prevent fluid flow outwardly through said enlarged bore portion, a retaining member removably received within said enlarged bore portion at its outward end, said stem extending slidably through said retaining member, spring means within said enlarged bore portion biased in compression between said piston portion and said retaining member to urge said valve member toward its seating position, and handle means removably secured to the outer end of said valve stem at said recess for withdrawing said valve member against the bias of said spring toward its open position.
